LEG FOR A BEDFRAME

Leslie K. Jackson, Lakewood, Ohio

Application December 5, 1957, Serial No. 48,784

Term of patent 14 years

(Cl. D5—2)

FIG.1

FIG.2

FIG.3

Figure 1 is an elevational view of a leg for a bedframe showing my design;

Figure 2 is a rear elevational view of the leg of Figure 1; and

Figure 3 is a top plan view thereof.

The caster unit shown in dot-dash lines in Figs. 1 and 2 is for illustrative purposes only.

I claim:

The ornamental design for a leg for a bedframe, as shown and described.
